NECKTIE

Harold E. Frampton, Larchmont, N. Y.

Application June 23, 1936, Serial No. 86,711

8 Claims.

(Cl. 2—146)

This invention relates to neckties generally but is particularly designed to produce an improved construction of long, scarflike ties of the type known as "four-in-hands".

5 The requirements for a satisfactory tie of that type include a sufficient stiffness and resilience in the folded fabric structure, especially in the longer, wider end thereof, while neither the end portions nor the neckband portion should be so thick as to produce undesirable bunches of material when the tie is knotted and draped about the wearer's neck.

10 It is the object of my invention to satisfactorily meet these and other requirements of the trade and the customer and at the same time reduce the cost of manufacture of the completed tie by dispensing with the usual lining fabric of relatively stiff material now generally present in the higher priced ties of this class, and also by adopting a 15 construction which is simple in manufacture and can be made up by machinery as well as by hand.

20 The best form of tie embodying my invention at present known to me, together with one minor modification thereof, are illustrated in the accompanying sheet of drawings in which—

25 Fig. 1 is a perspective view of a four-in-hand tie ready for use embodying my invention and made according to my improved construction.

30 Figs. 2, 4 and 5 are cross sections taken respectively along lines 2—2, 4—4 and 5—5 on Fig. 1, and

Fig. 3 illustrates in cross section a possible, slight modification.

35 Fig. 6 is a detail, longitudinal section of the tip portion of the long end of the tie taken on the plane of line 6—6 of Fig. 2, and shown on a larger scale.

40 The thickness of the fabric is exaggerated in all the sectional views for the sake of clearness, and throughout the drawing like reference numerals refer to like parts.

45 Referring to Fig. 1, the "long end", "short end", and "neckband" portions of the conventional four-in-hand tie are respectively indicated generally by the numerals 1, 2 and 5. The invention is especially advantageous when employed in making the long end 1 and is herein shown and described with reference thereto, but such construction might be extended further. Usually, 50 however, I prefer to make the neckband and short end of the tie thinner than the long end by using a lesser number of plies of the fabric therein in some such manner as shown in Fig. 4 for the said short end and in Fig. 5 for the said neckband portion.

55 The basic idea of means to ensure the production of a tie, the main body (long end) of which shall be sufficiently thin but still stiff enough to hold its original flat form during handling by the salesman and use by the customer, without

the insertion of any inner stiffening fabric, consists in the novel arrangement of the tie fabric shown in Fig. 2—and in slightly modified form in Fig. 3.

5 As shown in Fig. 2 the front face of the tie is formed as usual by a ply 7 of the material extending the full width of said face, but the novel features of my invention appear in the back portion of the tie which is made in two sections meeting along approximately the longitudinal center line thereof, each of said back sections being composed of a flattened coil formed by three flat plies of the material, each extending substantially the full width of one half section of the back surface. One such flattened coil extends from one side edge of the tie to said center line, while the other extends from said line to the other edge of the tie. As shown, each of said coils consists of an outer, back ply 8, an inner ply 9 adjacent the front ply 7, and an inner ply 10 lying between, 10 and being of sufficient width to completely fill, 15 the interior space between 8 and 9.

20 The adjacent inner edges of said flattened coils may abut one against the other and lie in the same plane as shown in Fig. 2 and may, or may not be connected together by light stitching 12. 25

To facilitate stitching of the two coil edges together, however, one might slightly overlap the other as indicated in the modification illustrated in Fig. 3 and be stitched together in that position as indicated at 11. In such case I prefer to prevent any possibility of such overlapped seam causing a ridge to appear along the front face of the tie, after pressing thereof, by inserting a narrow strip 13 which may be made of stiffer material 30 in the tie interior next to the front ply 7, as shown in Fig. 3. The advantage of this overlapping construction is that it facilitates the insertion of stitches 11, while its possible disadvantage results from occasionally causing a ridge 35 to show in the front face of the tie if the material of which the latter is made is thin and no strip 13 is inserted.

40 The adoption or omission of one or more of these last described features will be a matter of choice by the manufacturer determined by the conditions in any particular case. The exaggerated thickness of the material shown in Fig. 3 for clearness, of course, indicates a much greater ridge-forming tendency than would occur in 45 practice with ordinary fabric.

45 To economize material and reduce the thickness of the neckband portion some such arrangement as shown in Fig. 4 is preferably employed at that point. As there indicated a relatively 50 broad two-ply fold 20 forms the right hand section of the back portion of the tie, while a narrower fold with turned-in edge portion 21 forms the left hand section, the two edge portions of the flattened coils overlapping and being held to 55

60

gether by stitches 11 as before described. The narrow inner strip 13 of added material is also shown in Fig. 3, though it may be omitted from the neckband as well as at other points, as indicated in Figs. 2 and 5.

Still another arrangement of plies and folds may be used in forming the short end of the tie as shown in Fig. 5 where the main back portion of the tie at that point is composed of the 10 zigzag fold 17 of one edge portion of the fabric, while the other side area of the back portion is formed by a single fold 18 with a narrow inwardly folded edge portion 19 nested in the interior of the zigzag fold 17.

15 To save labor and also to avoid the production of ridges on the tie exterior the side edges of the blank of material from which the tie is made, as above described, may be left unhemmed as indicated at 15, 15, in Fig. 6,—as may also the 20 edge portion 16, of each innermost ply end, since both are hidden from view when the tie is completed. The end edges of the remaining two plies are preferably hemmed as indicated at 14, 14, because they are exposed to view. One important 25 advantage inherent in the above described construction results from the fact that when each side edge of the forming fabric is thus snugly nested in the bight of the fold formed by the two adjacent plies of the coil on that side of the tie, 30 said edges may be left unhemmed without danger of their raveling. Also such unhemmed edges are securely hidden from view and, most important of all, the ridge forming possibilities of such otherwise necessarily hemmed edges are 35 avoided.

I am aware that it has been heretofore proposed to form a tie having two 3-ply zigzag folds (as distinguished from the two flattened coiled portions employed in my invention) forming the 40 back portion thereof, but in such prior structures the two raw edges of the fabric were prone to ravel unless they were hemmed,—in which case the ridge forming difficulty above pointed out resulted.

45 Preferably the fabric forming the tie is cut on the bias to the weave, as indicated at 6 in Fig. 1 by the enlarged detail diagrams of the threads out of which the fabric is woven. This is in accordance with standard practice and gives the 50 completed tie a certain resilience and capacity for reassuming its normal shape after temporary distortion which may be experienced in handling, twisting to form the usual knot, and/or draping into desired position for use, and by my invention these essential qualities are secured without the use of any special lining fabric which would otherwise have to be basted to the tie-forming fabric proper. The result of the hereinbefore 55 described construction is a four-in-hand tie of 60 no more than permissible thickness, the desired resilience and long life with preservation of these qualities and its original shape.

Also the cost in manufacture of ties embodying my invention is low, as each is formed of a single 65 simple blank which can be folded readily into final shape and finished with little, if any, stitching throughout considerable portions of its length.

Various changes could be made in the details 70 of construction, folding, stitching, etc. without departing from the underlying novel principle of my invention which consists essentially of the special procedure described and resulting in the simple seven-ply fold throughout the long end of the tie, as shown in Fig. 2 or 3, so long as the

resultant article of manufacture is within the definition of the appended claims or of some of them.

Having described my invention, I claim:

1. A four-in-hand necktie consisting of a single 5 blank of cloth so folded that the main portion of the back of the larger, wider end portion constituting the main body of the tie called the "long end" is formed in two sections meeting along substantially the longitudinal center line of said 10 back portion and each composed of a flattened coil formed by three flat plies of the material, each of said plies extending the full width of one half section of the tie, one of said flattened coils extending from one edge of the tie to said 15 center line and the other extending from the other edge of said tie to said center line; whereby a unitary tie structure is formed of only medium thickness, but of sufficient stiffness to maintain its shape during use and handling. 20

2. A necktie such as defined in claim 1 in which the edges of said coils meeting along the said center line are stitched together.

3. A necktie such as defined in claim 1 which comprises a long end, a short end and a connecting neckband in which the neckband and short end are each composed of a lesser number 25 of folds than those present in the long end.

4. As a new article of manufacture a four-in-hand tie having a major portion of its long end 30 throughout all cross sections thereof composed solely of four thicknesses of a single folded blank of fabric, a medial portion of the fabric blank forming the face of said tie, and the portion at each side thereof being folded into a flattened 35 coil composed of three thicknesses of fabric each having a width equal to one half that of the tie body, said coils meeting along the medial line of the back of said tie.

5. A fabric necktie having a main body portion and end portions connected therewith, the long end portion thereof, at least, comprising fabric folded upon itself along a pair of spaced lines to form a face portion and a pair of back portions, the material of each back portion being 45 folded inwardly on itself along the medial line of the tie, the material in each back portion being further folded upon itself adjacent the first mentioned lines of fold and concealed therein, the free edges of each back portion extending to substantially the medial line of the tie and being concealed within the fold at said medial line. 50

6. A fabric necktie having a main body portion and end portions connected with the body portion, the end portions having their sides folded inwardly and multiply folded upon themselves so as to enclose between the multiple folds the raw edges of the fabric adjacent a medial line through the necktie. 55

7. A fabric necktie of the four-in-hand type, 60 the long end portion of which has its sides folded inwardly and double folded upon themselves forming superimposed layers, each of which side portions encloses a raw edge of the fabric terminating adjacent a medial line through the 65 necktie.

8. A fabric necktie having a long end portion and a short end portion connected together by a neckband portion, said end portions each including a face portion and side portions folded inwardly from said face portion, the inwardly folded portions being folded upon themselves and enclosing the raw edge of the fabric along a medial line through the necktie. 70
